YIELDABLE BELT BUCKLE

Robert C. Legat, New Britain, Conn., assignor to
 The G. E. Prentice Mfg. Co., Kensington, Conn.,
 a corporation of Connecticut

Application July 27, 1948, Serial No. 40,859

2 Claims. (Cl. 24—178)

1

This invention relates to belt buckles and has for its principal object the provision of an improved yieldable belt buckle.

It has heretofore been proposed to make belts stretchable to a limited extent either by forming the body of the belt or strap with an elastic construction, or by including an expansible unit in such belt body. One of the purposes of this invention is to provide a stretchable belt in which all or a substantial portion of the stretch is obtained from the belt buckle.

Another object of the invention is to provide an improved belt buckle having a yieldable strap anchoring means to render the entire belt stretchable, even though an ordinary non-stretchable leather strap may be attached thereto.

A further object of the invention is to provide a simple, inexpensive and neat construction for belt buckles, which will enable the latter to be readily manufactured from sheet material.

Other objects of the invention, as well as its advantages and novel features of construction, will become apparent after a perusal of the following description when read in connection with the accompanying drawings, in which Fig. 1 is a top plan view of the buckle end of a belt embodying the invention; Fig. 2 is a top plan view of the buckle per se, the buckle being partially broken away to show its construction more clearly; Fig. 3 is a back plan view of the belt buckle; Fig. 4 is a rear end view of the belt buckle; Fig. 5 is a sectional view taken along the line 5—5 of Fig. 2; Fig. 6 is a sectional view taken along the line 6—6 of Fig. 2 and Fig. 7 is a plan view of the blank from which the buckle is made.

In the drawings, the reference numeral 10 indicates generally, the buckle for the strap 11. At its attached end, the strap 11 is provided with a folded or looped portion 12, which extends over the top of buckle 10, around the strap or slide bar 13 of such buckle, and then under the buckle to a point in rear of the latter, where it is attached to the body of the strap 11, as by the usual snap 14. It will thus be noted that the looped strap portion 12 of the belt has a length substantially greater than one-half the length of the buckle 10 and is secured to a strap or slide bar 13 located intermediate the ends of such buckle.

The body of buckle 10 is made from an integral piece of sheet metal of any desired type. As is shown in Fig. 7 of the drawings, the buckle body includes a U-shaped piece of metal which

forms the outer surfaces of the buckle and which is composed of two leg portions 15, 16 and a front bar portion 17. During the blanking out operation, the leg portions 15 and 16, which form the sides of the buckle, are shaped into a channel form, and the front bar portion 17 is shaped to give it the configuration desired in the finished buckle. As a result of this initial shaping of the blank, the portions 15, 16 and 17 forming the U-shaped piece will be offset with respect to the remaining portions of the blank. Connected to the front and rear edges of the front bar portion 17, are extensions 18 and 19, which are bent inwardly along their lines of connection with such front bar portion until their under surfaces are in engagement with the under surface of the front bar portion 17, as is shown more clearly in Fig. 3 of the drawings. Connected to the outer side edges of the side portions 15 and 16, are extensions 20 and 21, respectively, which are bent or folded inwardly to form in each side of the buckle, a longitudinal chamber 22 extending the entire length of such side portions 15, 16. At the rear ends of the side portion 15 and its associated extension 20, are ears 15', 20' respectively, which are bent towards each other in rounded fashion to close the rear end of the chamber 22 formed by such portion 15 and extension 20. In a similar fashion, the ears 16', 21' provided at the rear ends of the side portion 16 and extension 21, respectively, are bent to close the rear end of the chamber 22 formed by the latter (note Fig. 4 of the drawings).

Intermediate the two side portions 15 and 16 and adjacent to the rear ends thereof, is a rear bar 25 constituted of a flat strip of sheet metal which is integral at its ends with the inner edges of such portions 15 and 16. As is shown in Fig. 4 of the drawings, the rear bar 25 is depressed with relation to the side portions 15 and 16, so that it extends across the buckle approximately midway of its thickness.

Spaced from the front bar portion 17 in the forward end of the buckle, is a tongue bar composed of a depressed strip 26 integral at its ends with the inner side edges of portions 15 and 16 and extensions 27 and 28, the latter together with strip 26 being bent to form a round transversely extending tongue bar. The extensions 27 and 28 are provided with central cutouts 27' and 28', respectively, which in the formed condition of such extensions, provide a means for maintaining the tongue 29 centered on the tongue bar.

It will be noted from Figs. 5 and 6 of the drawings, that the side portion 15 and its associated extension 20 are so formed that a longitudinal slot 30 extends from the rear bar 25 to the tongue bar 26. From the rear bar 25 to the rear ends of portion 15 and extension 20 and from the tongue bar to the front bar portion 17, portion 15 and extension 20 are formed to entirely close the chamber 22 in such regions. In a similar fashion, the side portion 16 and its associated extension 21 are formed to entirely close the chamber 22 formed thereby in the regions between the rear ends of such parts and the rear bar 25 and between the tongue bar and the front bar portion 17 and to provide a longitudinally extending slot 30 between the rear bar 25 and the tongue bar. The slots 30 formed in the side portions of the buckle serve as guides for the slide bar 13 whose outer ends extend through such slots into the chambers 22, 22 formed in the sides of the buckle (note Fig. 2 of the drawings). The slide bar 13 is provided at its ends with forwardly projecting legs 32, 32 which ride in the chambers 22 during the slidable movement of the slide bar 13 and cooperate with the walls of such chambers to maintain the slide bar 13 correctly positioned on the buckle during its sliding movements. This correct positioning of the slide bar 13 as well as its inadvertent removal from the buckle are assured by means of the up-turned rear edge portion 31 thereof, which coacts with the inner sides of the side portions 15 and 16 and the leg portions 32, 32 to accomplish such results. The slide bar 13 is normally maintained in a forward position by means of a pair of springs 33, 33 seated at their rear ends in the closed pockets formed at the rear ends of chambers 22, 22 and bearing with their front ends against the outer end portions of the slide bar 13 in the chambers 22, 22.

It will be understood from the foregoing, that in the normal positions of the parts, the springs 33, 33 will maintain the strap or slide bar 13 in its forward or advanced position with the front folded edge of the belt portion 12 engaging the tongue bar 26. The said edge of the belt portion 12 is provided with a cut-out 34 in the region of the tongue 29 to permit such edge to engage throughout its length with the tongue bar 26; (note Fig. 1 of the drawings). In this advanced position of the slide bar 13, the legs 32, 32 thereof, will be located in the closed portions of chambers 22, 22 in advance of the tongue bar 26, as is shown more clearly in Fig. 2 of the drawings. When any stress is exerted on the belt strap 11 tending to move the slide bar 13 rearwardly against the resilient force of springs 33, 33, such bar 13 will slide rearwardly in the slots 30, 30 to a position where the built up force in the contracted springs will balance the force on the belt strap. The slide bar 13 can be retracted approximately one-half an inch before the springs 33, 33 are contracted to the extent that they become in effect, solid stop members. This range of movement is believed to be sufficient to take care of all normal requirements of needed stretch in the belt for a particular adjustment of the belt on the user, but may be increased or decreased by varying the construction of the springs. As soon as such need for stretch has ceased, the stored up energy in the springs 33, 33 will advance the slide bar 13 until the folded front end of belt portion again engages the tongue bar 26 or to some intermediate position in the slide bar's range of movement;

where the energy in springs 33, 33 will balance any remaining force on the belt strap.

It will also be seen from the foregoing, that the buckle of applicant's belt, although made from sheet metal, is attractive and neat in appearance, and gives the visual appearance of a buckle made in the ordinary manner. At the same time, the buckle is sturdy in construction and will efficiently perform its functions for a long period. Because of the fact that the buckle is made of sheet metal material, it can be made at relatively low cost and in large numbers by simple blanking and forming operations.

While I have described and illustrated a preferred form of my invention, it will be evident to those skilled in the art, that modifications and changes may be made therein without departing from the spirit of the invention or the scope of the appended claims.

I claim:

1. A self-contained belt buckle unit comprising a body portion having a pivotally mounted buckle tongue, said body portion being made of an integral piece of sheet metal and including a pair of substantially tubularly-shaped side portions forming the sides of the buckle, a front bar portion integral at its ends with the front ends of said side portions and forming a rest for the free end of the buckle tongue, and a rear bar portion integrally connected at its ends with the rear ends of said side portions so as to be positioned within the looped end of the strap connected to such buckle, stop means provided on said side portions between said front and rear bar portions and in spaced relation thereto, each of said side portions being provided with a longitudinally extending slot opposed to the slot of the other side portion and extending from said stop means to said rear bar portion, each of said side portions having closed rear ends and being substantially closed along their opposed inner edges from said stop means to said front bar portion, a transverse strap bar to be positioned within such looped strap end located between said stop means and said rear bar portion, the ends of said strap bar extending directly through such slots into the interiors of said side portions and being slidably movable in said slots longitudinally of said side portions between said stop means and said rear bar portion, said stop means limiting the forward movement of said strap bar toward said front bar portion, said strap bar being provided on its inwardly projecting ends with longitudinally extending legs of substantial length located wholly within the interiors of said side portions and during the sliding movements of said strap bar away from and toward said stop means coacting with portions of the interior walls of said side portions spaced from said slots to maintain said strap bar correctly positioned on the buckle during its sliding movements, and helical springs wholly positioned within said side portions between said strap bar and the rear end of said buckle and normally maintaining said strap bar in engagement with said stop means and yieldingly resisting sliding movement of said strap bar away from said stop means and toward said rear bar portion, said springs each having a length less than the distance between said stop means and the rear ends of said side portions and being seated at one end on the closed rear ends of said side portions and at the other end on the inwardly projecting ends of said strap bar.

2. A self-contained belt buckle unit comprising a body portion made of an integral piece of flat

sheet metal and including a pair of substantially tubularly-shaped side portions forming the sides of the buckle, a front bar portion integral at its ends with the front ends of said side portions and forming a rest for the free end of the buckle tongue, a rear bar portion integrally connected at its ends with the rear ends of said side portions so as to be positioned within the looped end of the strap connected to such buckle, and a tongue bar integrally connected at its ends to said side portions at points located between said front and rear bar portions and spaced therefrom, said front bar portion consisting of a flat strip portion having a pair of longitudinal extensions integral with the side edges of said strip between said side portions and folded toward each other under said strip, said tongue bar consisting of a flat strip portion having two spaced longitudinal extensions integral with each side edge of such strip between said side portions and bent to form two spaced tubular portions, a tongue pivotally connected to said tongue bar between the spaced tubular portions thereof, and each of said side portions being provided with a longitudinally extending slot opposed to the slot of the other side portion and extending from said rear bar portion a distance not greater than the length of the space between said rear bar portion and said tongue bar, each of said side portions having closed rear ends and being substantially closed along their opposed inner edges from said tongue bar to said front bar portion, a transverse strap bar to be positioned within such looped strap end located between said tongue bar and said rear bar portion, the ends of said strap bar extending directly through such slots into the interiors of said side portions and being slid-

ably movable in said slots longitudinally of said side portions between said tongue bar and said rear bar portion, and helical springs wholly positioned within said side portions between said strap bar and the rear end of said buckle and normally maintaining said strap bar biased toward said tongue bar and yieldingly resisting sliding movement of said strap bar away from tongue bar and toward said rear bar portion, said springs each having a length substantially less than the distance between said tongue bar and the rear ends of said side portions and being seated at one end on the closed rear ends of said side portions and at the other end on the inwardly projecting ends of said strap bar.
